UNITED STATES PATENT OFFICE.

WILHELM LOEBEN, OF DRESDEN-A, GERMANY.

CORE HOLDER FOR ARTIFICIAL FLOWERS.

Application filed March 23, 1928, Serial No. 264,160, and in Germany March 24, 1927.

This invention relates to the fastening of cores K (Fig. 1), which are enclosed in a sheath, (preferably of viscose film) twisted together above the core to form a plait Z, in 5 artificial flowers. The core will usually consist of chocolate or other sweetmeats, but may also be of any other article to serve as a small present or surprise, and takes the place in the 10 artificial bloom of the so-called gravel, that is, of a part of the bloom which is massive in comparison with the petals. Artificial fruit can of course be secured to twigs in a similar manner.

The object of the invention is to provide for 15 the exchangeable securing of such cores. This object is attained by means of a sleeve, which is intended to be connected with the peduncle of the flower and which is provided with inwardly directed teeth into which the 20 core can be introduced without resistance if the plait is tightly twisted together or if the core is rotated in such a direction as to twist the plait together. If the core is then slightly twisted in such a direction as to unbraid the 25 plait, the teeth catch in the plait and prevent it from rotating, thereby causing a partial unbraiding of the plait, which is now mounted firmly enough in the sleeve not to come out even if the flower is accidentally shaken or 30 knocked. It comes out however if the core is again twisted in such a direction as to coil up the plait, and a pull is at the same time exerted thereon.

The inventive idea hereinbefore outlined 35 may be embodied, as regards the formation of the teeth, in various ways, while the sleeve may be of any desired shape, to enable the core to be formed for example for the calyx of a rose.

Other objects as well as details of construction whereby my invention may be carried out will be apparent from the following description taken in connection with the accompanying drawings, wherein:—

40 Figure 1 is a perspective view of a core of an artificial flower;

Fig. 2 is a perspective view of an artificial flower embodying my invention;

Figs. 3, 5, 7 and 9 are cross sectional views 50 of different modifications of the securing sleeve; and,

Figs. 4, 6, 8 and 10 are cross sectional views of different modifications of the sleeve.

Figure 2 shows by way of example a poppy

bloom with a core K of which the core holder 55 H is shown separately in Figs. 3 and 4 on a larger scale. The peduncle 1 penetrates from below into the sleeve H, which has a suitable covering and is held fast upon the peduncle bly a wire 2. The wire 2 is passed through a 60 hole 3 in the side of the sleeve and bent to form a hook. The upper edge of the sleeve is bent inwards and forms teeth 4, which are preferably shaped like a ratchet wheel, as shown. For the elucidation of the method 65 of fastening it may be pointed out that if the core K (Fig. 1) is held with the left hand and the sheath is twisted together in the direction of the arrow z with two fingers of the right hand, this involves a relative rotation of the 70 core in the direction of the arrow k. The consequence is that the plait Z, which has somewhat the appearance of a screw with a steep left-handed thread, as the core rotates in the direction of the arrow k, is twisted 75 more firmly together, whereas with the rotation in the opposite direction it is untwisted, if the plait meets in either case with any resistance hindering it from rotating with the core. Thus the plait Z can be introduced 80 without resistance into the sleeve H either by simply pushing it in, if the teeth 4 let it pass smoothly, or else by rotating it in the direction of the arrow k and thereby twisting the plait more closely together, if the latter does not pass smoothly between the teeth 4. 85

When, however, the core is turned slightly in the opposite direction, the folds produced by the twisting up of the plait bear against the teeth and therefore meet with a resistance, so that the plait is somewhat untwisted and the 90 teeth now penetrate into the plait and hold it fast against a pull. By a corresponding background rotation, that is, a rotation in such a direction as to twist the plait together, the core can easily be released again and 95 taken out.

It is not essential that the teeth should be in the form of ratchet teeth. If they are in the form of equilateral triangles it is immaterial whether the plait is coiled up in the direction of the arrow z or in the opposite direction, provided the core is rotated in a winding-up direction when inserting and removing and in an unwinding direction when fixing the plait. Ratchet-shaped teeth give, however, a better action, because for the sake of simplicity of manipulation it can always 100 105

be seen that the plait is always twisted together in the same direction of rotation.

The remaining figures illustrate further constructional possibilities. According to 5 Figs. 5 and 6 the sleeve H is formed of a rolled-up strip of sheet material, the inwardly bent inner edge of which forms a ratchet tooth 5 extending throughout the entire length of the sleeve.

10 According to Figs. 7 and 8 the entire sleeve is made star-shaped, with a cross section resembling a ratchet wheel, the vertices 6 of the indentations forming the ratchet teeth.

According to Figs. 9 and 10, tongues 7 are 15 cut out of the sleeve wall and bent inwards to form the ratchet teeth. The action is the same in all these cases.

What I claim is:—

1. An artificial flower comprising a 20 duncle, a plurality of petals secured thereto, and securing means fixed in said flower adapted upon insertion and rotation in one direction of a core having a plaited stem to hold

said core therein and upon rotation in the opposite direction to permit its removal. 25

2. In an artificial flower, means for holding a core therein having a plaited stem comprising a sleeve in said flower fixed to the stem, securing means in said sleeve adapted upon insertion and rotation of the core in one direction to hold said core and upon rotation of said core in the opposite direction to permit its removal.

3. In an artificial flower, means for holding an inner core therein having a plaited stem 35 comprising a sleeve fixed in said flower, inwardly directed projections in said sleeve adapted upon insertion and rotation of the core in one direction to engage and hold the core therein and upon rotation of said core 40 in the opposite direction to permit its removal.

In testimony whereof I have signed my name to this specification.

WILHELM LOEBEN.
